UNITED STATES PATENT OFFICE.

WALTER L. ROTHSCHILD, OF NEW ROCHELLE, NEW YORK.

CARD FOR HOLDING BUTTONS.

1,401,736.

Specification of Letters Patent. Patented Dec. 27, 1921.

Application filed March 31, 1920. Serial No. 370,297.

To all whom it may concern:

Be it known that I, WALTER L. ROTHSCHILD, a citizen of the United States, and a resident of the city of New Rochelle, county 5 of Westchester, and State of New York, have invented a new and useful Improvement in Cards for Holding Buttons, of which the following is a specification.

Heretofore buttons have been secured to 10 cards by sewing with stitches which pass through the holes in a button and the card, which stitches are made by hand. This is a slow and expensive way of securing buttons, although it was the only practical way 15 in many cases.

The object of my invention is to provide a simple, easy and effective means for securing buttons which will allow an easy removal or replacement of the buttons on the card. 20 This object is accomplished by my invention, some embodiments of which are herein-after more particularly set forth.

For a more detailed description of my invention, reference is to be had to the accompanying drawings, forming a part thereof, 25 in which—

Figure 1 is a plan view of one embodiment of my invention, and

Fig. 2 is a cross section of the same with 30 out the buttons in place.

Fig. 3 is a cross sectional view of the same with the buttons in position,

Fig. 4 is a modification of the invention shown in the preceding figures, and

Fig. 5 is a cross section of the structure 35 shown in Fig. 6 with a button added.

Figs. 6, 7, 8 and 9 show further modifications, Fig. 9 being a cross section of Fig. 8.

Throughout the various views of the drawings, similar reference characters designate 40 similar parts.

My improved button holder 1 may be made of cardboard or any other suitable material, and is preferably made of sheet material, which is folded to form flaps 2 at its longitudinal edges, partially secured to the back 5 by glue 3 or any other suitable means, such as stitching or wiring or what not. This securing is so proportioned that the 45 flexing of the flap 2, on the insertion of the button 4 as shown in Figs. 3, 5 and 9 induces sufficient pressure to retain the button in place. Each button 4 rests between the in-

terior of the flaps 2 and the back 5 of the holder 1. These buttons may be inserted at 55 either end or, if desired, the ends may be secured so that none may escape.

In Figs. 4 and 5 the foregoing structure is modified so that shank buttons 6 may be secured firmly in place. This is done by providing a longitudinal crease 7 in the center of the back 5, as indicated, which crease forms a recess with ample space for each shank.

In Fig. 6 the structure is modified yet in 65 another way by stiffening the back 5 by means of a suitable stiffener 8 which may be of card-board or corrugated paper or anything else that is suitable for the purpose.

In Fig. 7 the back 5 is shown perforated 70 at 9 so that shank buttons may be inserted if desired and held firmly in place when in position. This embodiment of my invention may be filled or emptied by inserting or removing the buttons while the back is flexed 75 so as to form a convex surface next to the buttons.

The embodiment of my idea shown in Figs. 8 and 9 is exactly the same as shown in Fig. 2, except that a band of paper or other material of a similar nature 10 is put about the package so as to leave the ends uncovered and the side edges covered, as indicated, except that they are uncovered to a greater or less extent, as shown. The purpose of this band is to hold the back 5 and flaps 2 in proper relation at all times so that under no circumstances will the buttons 4 work loose while being stored, transported or displayed.

In the embodiment shown in Figs. 1 to 7 inclusive of my invention, all buttons may be easily removed by flexing the back 5 so as to make it convex on the side next to the buttons and in the embodiment shown in 85 Figs. 8 and 9 this may be done after the paper band 10 has been removed.

It will be understood that in all embodiments of my invention, the flaps 2 must press the buttons 4 or 6 with sufficient firmness to hold them true and in place at all times.

In view of the foregoing, it is obvious that my improved button card and holder acts 105 without stitches and the buttons may be readily inserted or removed individually or

collectively and that when in position in the card they are well protected and not allowed to work loose.

While I have shown and described some 5 embodiments of my invention, it is obvious that it is not restricted thereto, but is broad enough to cover all structures that come within the scope of the annexed claims.

Having thus described my invention, 10 what I claim is:

1. An article of the class described comprising a button-holding card having a back having its edges infolded to form a pair of spaced-apart button-retaining flaps, said 15 flaps being secured to the back for a portion

of their width, with their unsecured flexible edge-portions overlying the edges of the buttons and pressing the same against the back.

2. An article of the class described comprising a button-holding card having a back, 20 having a pair of its edges infolded to form a pair of spaced-apart coöperating flaps, with the inner faces of said flaps secured to the back for a portion of their width, and having unsecured flexible edge portions 25 adapted to overlie the edges of the buttons and press the same against the back, said card being capable of being longitudinally flexed to eject the buttons therefrom.

WALTER L. ROTHSCHILD.
